UNITED STATES PATENT OFFICE.

ROBERT EDWIN MATTHEWS, OF MONTREAL, QUEBEC, CANADA.

SCARECROW.

1,286,380.

Specification of Letters Patent. Patented Dec. 3, 1918.

Application filed December 8, 1917. Serial No. 206,302.

To all whom it may concern:

Be it known that I, ROBERT EDWIN MATTHEWS, a subject of the King of Great Britain, and resident of 12 Oldfield avenue, in 5 the city of Montreal, in the Province of Quebec, in the Dominion of Canada, have invented certain new and useful Improvements in Scarecrows, of which the following is a specification.

10 The invention relates to improvements in scarecrows as described in the present specification and illustrated in the accompanying drawings that form part of the same.

15 The invention consists essentially of the novel construction and arrangement, whereby a figure of substantially imperishable material is supported so as to be subject to the winds in their courses.

20 The objects of the invention are to devise a figure to scare the crows from the grain fields, that will, with ordinary care, last indefinitely, to facilitate the operations of a farmer by furnishing an article, which can be changed from one place to another 25 at no risk of the dislocation of its make up, to demonstrate to the birds the good properties of the imitation by its simple movements and generally to provide a novel means of guarding the crops that will prove 30 economical, durable and serviceable.

In the drawings, Figure 1 is a front or rear elevation of the figure as the case may be.

Fig. 2 is a vertical sectional view.

35 Fig. 3 is a cross sectional view at the arms.

Fig. 4 is a plan view of the head piece.

Like numerals of reference indicate corresponding parts in each figure.

40 Referring to the drawings, the numeral 1 indicates the torso or body of the figure, which narrows from the shoulders 2 to the neck 3.

45 The body 1 is preferably made of sheet metal or other suitable material, said body having the lugs 3' and 4 forming the eyes 5 projecting outwardly intermediately of the height and in vertical alinement.

50 The head 6 also of sheet metal or other suitable material is secured to the neck 3 by the rivet 7 and may or may not turn from one side to the other as desirable.

The head piece 8 is a disk of metal or other suitable material and is slotted at 9

to fit over the head 6, so that the latter will 55 project thereabove between the cross sails 10.

The sections 11 and 12 form the arms and are also of sheet metal or other suitable material and these sections are flexibly joined by the rivets 13 and flexibly joined to the 60 body by the rivets.

The sections 14 and 15 form the legs and are joined together by the rivets 16, and are joined to the body by the rivets 17 and to the feet 18 by the rivets 19, all of these 65 parts being preferably of similar material to the body.

The rod 20, having the collar 21 toward the upper end, is inserted through the eyes 5, until the collar 21 abuts the lug 4, the 70 lower end of said rod is pointed so that it may be planted in the ground at any place and removed with ease, thus the figure will swing freely on said rod and as the lugs are centrally arranged on said figure, the 75 movements are irregular and natural enough to complete the suggestion of a living figure.

The head, body and other parts may be painted, lithographed or otherwise colored to more fully carry out the idea of the human figure guarding the field. 80

The figure of a man is shown and described herein, but other forms may be adopted according to its use, which need not necessarily be confined to scaring crows. 85

It will be seen that the figure, when mounted on the rod and the latter firmly stuck into the ground, will be free to rotate, therefore, as the wind meets any of its surfaces, the said figure will turn to a limited extent and it can never stand still for the sails formed by the projecting head and cross pieces will always provide surface to keep the figure moving, no matter which way the body is blown. 90

95 Various changes may be made in both the construction and uses of this device without departing from the spirit of the invention so long as they are within the scope of the claims for novelty following. 100

What I claim is:—

1. A scarecrow comprising a supporting pole adapted to be rigidly secured and a figure formed of sheet material and cut out to represent limbs, body and head, said pole 105 engaging bearings on said body for the horizontal rotation of said figure around said pole without hindrance.

2. A scarecrow or the like, comprising a figure having jointed member and a head piece forming cross sails, and a rod secured to said figure, the latter being freely rotatable and liable to the action of the winds.
3. A scarecrow or the like, comprising, a head, body, legs, arms and feet formed in various parts and jointed, a head piece having a slot for said head to project through

and corresponding cross sails and a rod 10 attached to said body and permitting the latter free rotation.

Signed at the city of Montreal, Quebec, Canada, this 20th day of November 1917.

ROBERT EDWIN MATTHEWS.
